Primary Examiner — Lauren R Calve(57) **CLAIM**

The ornamental design for a door pull for sliding doors, as shown and described.

DESCRIPTION

FIG. 1 is a left side elevational view of a door pull for sliding doors showing my new design, the right side elevational view being a mirror image thereof;

FIG. 2 is a front elevational view thereof;

FIG. 3 is a rear elevational view thereof;

FIG. 4 is a top plan view thereof;

FIG. 5 is a perspective view thereof; and,

FIG. 6 is another perspective view thereof, mounted on a sliding door shown in broken lines.

The broken line portions of the article shown in FIGS. 3, 4 and 5 do not form a part of the claimed design.

The broken and phantom lines in FIG. 6 are to show environment and do not form part of the claimed design.
